UNITED STATES PATENT OFFICE.

WILLIAM PLEASANT BLISS, OF AURORA SPRINGS, MISSOURI.

ATTACHMENT FOR BUGGY-TOPS.

950,038.

Specification of Letters Patent. Patented Feb. 22, 1910.

Application filed August 9, 1909. Serial No. 511,949.

To all whom it may concern:

Be it known that I, WILLIAM P. BLISS, a citizen of the United States, residing at Aurora Springs, in the county of Miller and 5 State of Missouri, have invented certain new and useful Improvements in Attachments for Buggy-Tops; and I do declare the following to be a full, clear, and exact description of the invention, such as will enable 10 others skilled in the art to which it appertains to make and use the same.

This invention relates to attachments for buggy tops.

One object of the invention is to provide 15 an attachment adapted to yieldingly connect the main props of the top with the rear axle of the buggy, whereby the jarring or sudden jerking usually received by the top of the buggy when the wheels run into a rut or 20 over an obstruction, will be substantially eliminated.

Another object is to provide a device of 25 this character by means of which the top of the buggy when lowered will be prevented from forcibly dropping, which frequently results in the breaking of the bows or other part of the top.

With the foregoing and other objects in 30 view, the invention consists of certain novel features of construction, combination and arrangement of parts, as will be more fully described and particularly pointed out in the appended claims.

In the accompanying drawings, Figure 1 35 is a side view of a portion of a buggy showing the application of the invention thereto and showing the buggy top in raised position; Fig. 2 is a similar view, showing the buggy top in lowered position; Fig. 3 is a 40 detail side view of one of the main braces of the buggy top showing the attachment connected thereto.

Referring more particularly to the drawings, 1 denotes the main prop or brace of the 45 buggy top 2, said prop consisting of an upper section 3 connected to the upper portion of the buggy top in the usual manner and a lower section 4 which is connected at its lower end to the top supporting bolt 5 in the 50 usual manner. The sections of the prop are connected together by the ordinary form of rule joint, whereby the prop may be "broken" when the top is lowered. On the lower pivoted end of the prop is formed a 55 downwardly projecting extension 6, on the

lower end of which is formed a hook 7. To the hook 7 on the extended end of the prop is connected one end of a coiled spring 8, the opposite end of which is connected to a hook 9 formed on the clamping plate 10 of a clip 60 11 secured to the rear axle 12 of the vehicle. It will be understood that the main props on both sides of the top are provided with extensions 6 and have connected thereto the springs 8. By providing the springs 8 and 65 connecting the same to the top prop and rear axle, as herein shown and described, the top of the buggy or vehicle will be yieldingly braced and held against violent jarring or 70 jerking motion when the wheels of the vehicle run into ruts or over obstructions, thus preventing the racking of the top. The springs when arranged in the manner described, also prevent the rebounding of the vehicle body and the consequent bouncing 75 or tossing of the occupants thereof, as well as obviating the danger of breaking the vehicle springs which frequently occurs from the excessive rebounding movement of the body. The attachment also serves the purpose of holding the vehicle body in a level 80 position. By extending the end of the main props of the top below the lower pivotal connection of the latter and connecting the springs to the extensions, as shown, the pressure of the springs is utilized to assist in gradually lowering the top, thus preventing the same from forcibly dropping onto the supporting bolts and thus injuring the top. The springs will also serve to yieldingly 85 hold the top when in lowered position and prevent the same from shaking and jarring 90 when the vehicle passes over rough roads.

From the foregoing description, taken in connection with the accompanying drawings, the construction and operation of the invention will be readily understood without requiring a more extended explanation.

Various changes in the form, proportion 95 and the minor details of construction may be resorted to without departing from the principle or sacrificing any of the advantages of the invention, as defined in the appended claims.

Having thus described my invention, what 105 I claim is:

1. In an attachment for buggy tops, a top prop having its lower section extended longitudinally beyond its pivotal point, a 110 spring connected at one end to said exten-

sion, a clip adapted to be secured to the rear axle, and means to connect the lower end of said spring with said clip.

2. In an attachment for buggy tops, a main top prop having a rigid member on the lower end of its lower section extending longitudinally in the same plane beyond the pivotal point thereof, and provided on its free end with a hook, a clip for connection to 10 an axle having a hook extending upwardly

therefrom, and a coiled spring engaged at its opposite ends with said hooks respectively.

In testimony whereof I have hereunto set my hand in presence of two subscribing witnesses. 15

WILLIAM PLEASANT BLISS.
